C. CHISHOLM,
ADDRESS PLATE HOLDER.
APPLICATION FILED SEPT. 16, 1920.

Patented Dec. 12, 1922.
2 SHEETS—SHEET 2.

UNITED STATES PATENT OFFICE.

CLIFTON CHISHOLM, OF CLEVELAND, OHIO, ASSIGNOR TO AMERICAN MULTIGRAPH COMPANY, OF CLEVELAND, OHIO, A CORPORATION OF OHIO.

ADDRESS-PLATE HOLDER.

Application filed September 18, 1920. Serial No. 410,710.

To all whom it may concern:

Be it known that I, CLIFTON CHISHOLM, a citizen of the United States, residing at Cleveland, in the county of Cuyahoga and State of Ohio, have invented a certain new and useful Improvement in Address-Plate Holders, of which the following is a full, clear, and exact description, reference being had to the accompanying drawings.

10 This invention relates to address plates and holders therefor. It is particularly concerned with plate-like mounting frames for carrying the plates to facilitate conveying and handling both mechanically and manually.

In the use of address plates for multi-copy work, letter work, etc., the plates are ordinarily stored in filing drawers and are removed from the filing drawers and presented to the printing mechanism and are then again assembled in the same or a corresponding order and stored. By my invention the conveying of these plates to and from the machine, the storage and mechanical indexing thereof, as well as the mechanical automatic selection of the plates for addressing purposes is greatly facilitated. The machines in which such address plates are useful are those having automatic means for removing the plates from a column or stack and conveying them past the inking and printing mechanism, and then depositing them in another stack or column, the conveying being accomplished by the use of flexible members engaging the sides or ends of the plates. An example of such a machine, is that shown and described in my co-pending application on an address printing mechanism filed November 26th, 1920

40 Serial No. 426,412.

The particular objects of my invention include the provision of plate holders having such characteristics that the holders with the address plates may be most conveniently handled by addressing machines used for printing addresses on letters, circulars, cards, envelopes, etc., and the particular invention is concerned with the construction of such a plate holder, which is simple and durable and may be comparatively cheaply manufactured.

Another object contemplated by the present invention is to provide a plate holder that may be readily stacked in the maga-

zine of such a machine directly from a filing 55 drawer and removed therefrom, conveyed past the inking and printing mechanism and returned to the drawer in proper filing order.

Another object of the present invention is to provide means on the plate holder for 60 controlling the ink supplying means in an addressing machine whereby the inking means is prevented from coming in contact with any portion of the device except the embossed characters in the plate carried 65 thereby.

Another object of the present invention is to provide means whereby the printing matter carried by the holder may be readily discerned from either side of the holder. 70

Another object of the invention is to provide means for preventing the printing plate from becoming dislodged when passing through the machine.

A further object is to provide means for 75 preventing the indexing means carried by the holder from becoming displaced when passing through the machine.

The invention is hereinafter more fully described in connection with a convenient embodiment of the same as shown in the drawings, and the essential characteristics of the invention are set forth in the claims.

Referring to the drawings, Fig. 1 is a front elevation of the plate as it is seen from the front of the filing drawer, while Fig. 2 is a view of the plate holder as seen from the rear of the drawer; Fig. 3 is an end view of the plate holder which clearly shows its compact and comparatively thin construction, while Fig. 4 is a view of the embossed printing plate which is adapted to be slidably mounted on the plate holder; Fig. 5 is a fragmentary section substantially along the line 5—5, of Fig. 1, while Fig. 6 is a section along the line 6—6 of the same view; and Fig. 7 is a similar section substantially along the line 7—7; in Fig. 8 I have shown a section along the line 8—8 of Fig. 1; and Fig. 9 is a section substantially along the line 9—9 of Fig. 1; Fig. 10 is a view of an adjustable indexing tab which is adapted to be quickly attached at the top of the plate holder; Figs. 11, 12, 13 and 14 are sectional views of the plate holder in transit through 105 an addressing machine.

The plate holder is particularly designed to be economically formed from a single

sheet of metal in such a manner that the thickness of the holder in combination with the plate may be very small in order that a large number of the holders may be stacked 5 in one drawer.

Referring to the various parts by numerals, in Fig. 1, a thin sheet metal blank with the rectangular opening 3 and the irregular opening 4 is bent along the parallel 10 edges 2 and 10 to form the clips 11 and 12, which provide retaining means for holding the printing plate rigidly in the holder and against the back of the plate holder 9. An inverted head 18 is also formed in the sheet 15 at the time the openings 3 and 4, as well as the indented portions 7 and 8 are formed.

I also have provided recesses 15 in the printing plate 16, which are spaced equal 20 distances from the ends of the plate, anyone of which is adapted to be engaged by the indented portion 7 of the clip 12, and with the plate stop lug 33 serves to accurately register the printing plate as it is being mounted 25 on the holder and to retain it in that position thereafter. The corners of the plate are also trimmed to facilitate the sliding of the plate as it is being inserted. This movement is inwardly from the right hand side of the plate holder. The opening 3 in the 30 holder provides access to the back of the plate for gripping it when inserting and removing the same.

This opening also exposes the back of the plate so that the printing characters embossed thereon may be easily read, as the characters appear in their normal reading 35 position from the back of the thin plate into which they are embossed.

The identifying card 19 may be inserted 40 from the same side of the holder, and the indented portion 8 of the clip 18 serves as a stop for the same on the right hand side of the holder.

It is essential that means be provided for 45 protecting the embossed characters on the plate when the holders are stacked in filing drawers to protect the backs of the holders from coming in contact with the adjacent plates, and it is also desirable to provide 50 a lateral stiffening means on the holder. To accomplish this I prefer to form the rails 13 and 14 by turning the ends of the sheet from which the holder is shaped over and 55 under the body portion of the holder with the upper ends 36 protruding beyond the upper margin of the holder. The lower ends of the rails are adapted to be engaged by flexible conveying means while the upper extending ends may serve to protect the 60 removable indexing tab 20, as will be herein-after described.

To facilitate the locating of a certain 65 holder contained in the filing drawer I have provided an indexing tab which may carry letters, names of cities, etc., and which may

be adapted to be slidably mounted at the top of the holder. A tab which may be conveniently used is shown in Fig. 10. This tab is formed of a narrow strip of metal with a letter face 21 and a clamping portion 22 70 with its end slightly beaded and the elongated portion 23 on the back of the tab, which acts as a stabilizer when the tab is snapped over the top of the plate holder. This tab may be placed along the top of the 75 holder anywhere within the width of the shorter part of the opening 4.

To insure proper inking of the embossed printing plate and to avoid any consequent smearing of the ink I have incorporated an 80 inking controlling means directly within the plate holder. On the front of the holder and at the sides I have provided parallel indentations 25 in line with the rails 13 and 14 and opposite the ends of the printing 85 plate which may serve the following purpose:—as the chain 34, with properly spaced raised links 35, passes beneath the stack of holders in the magazine of the machine, the links 35 engage the ends of the rails 13 and 90 14 and convey it from beneath the stack of holders to the ink roller 26, at which time the projecting ends 36 come in contact with the ink roller wheels 27 and raise the ink roller to clear the indexing tab 20 and clip 95 12, and upon reaching the indented portions 25 of the holder the wheels 27 lose contact with the holder, thus causing the ink roller to come in contact with the raised or embossed portions 17 of the printing plate. By 100 this arrangement I prevent the ink roller from coming in contact with the plate holder and only in contact with those portions of the printing plate which are embossed. As the plate passes the ink roller, the roller is 105 again raised by the portion of the rail 37, which holds the roller out of contact with the portion 11 of the plate holder. In Fig. 14 I have shown the plate holder passing over the rotary platen 30 and beneath the compression roll 31. While being conveyed by the chain 32 and when passing between the rolls 31 and 30, the holder becomes separated 110 from the conveying chain 34 and is guided by suitable means to the filing drawer, where 115 it is restacked automatically in proper order.

It is to be seen from the foregoing description of my invention that I have constructed a plate holder which is of such 120 shape that it can be readily and economically formed from a single sheet of thin metal, and which can be conveniently stored in large numbers and in proper order in a comparatively small space.

It is also evident that by providing an opening in the back of the plate holder directly under the plate location, it is possible to identify the printing characters of the plate by reading the embossed letters as seen 130

from the rear of the holder or by reading the identifying card carried on the front or printing side of the holder.

It will be understood, furthermore, that by having this opening in the back of the plate holder the act of mounting the printing plate upon the holder or the dismounting of the same is greatly expedited, as it is possible to grasp both sides of the plate when 10 sliding it on the holder.

It will also be seen that by having the ink controlling means embodied directly in the holder so that the inking period is determined by the relative movement of the 15 holder to the inking mechanism, I have eliminated the possibilities of the holder or plate gathering ink at any place except where desired, and consequently avoid soiling the correspondence being addressed by 20 the plates.

Having thus described my invention, I claim:

1. An address plate holder having a printing plate mounted thereon, and having an 25 identifying card retaining means located above said plate and extending over the upper edge of the same, whereby said card retaining means may also act as part of the plate retaining means.

2. In a device of the character described, a plate holder having a printing plate and an identifying card removably mounted thereon, and elongated apertures through which the 35 printed matter on said plate and said card may be read, and a removable index tab mounted above one of said apertures.

3. In a device of the character described, a plate holder having a printing plate mounted thereon, and having means for controlling an inking mechanism.

4. In a device of the character described, a plate holder having a printing plate mounted thereon, and having means for maintaining the ink roller of an inking mechanism out of contact with the surfaces 45 of said holder.

5. In a device of the character described, a plate holder having an embossed printing plate mounted thereon, and having 50 means for maintaining the ink roller of an inking mechanism out of contact with the unembossed surfaces of said printing plate.

6. In a device of the character described, a plate holder having a printing plate mounted thereon, and means for controlling an ink roller including indented portions in 55 said holder opposite the ends of said plate, whereby cylindrical members mounted coaxially with said ink roller may lose contact 60 with the surface of said holder, and permit the ink roller to come in contact with the embossed sections of said plate.

7. As an article of manufacture, a plate holder having transverse flanges on opposite 65 sides and having the longitudinal sides fold-

ed over to form retaining means for a printing plate and an identifying card.

8. As an article of manufacture, a plate holder having a part of its longitudinal margins turned inwardly and substantially parallel with the surface of the body part of the plate holder, one of said turned portions being inwardly beaded to define channel parallel with said longitudinal margin. 70

9. As an article of manufacture, a plate holder having upper and lower longitudinal portions folded back upon the undistorted section of the holder, said upper portion having an elongated aperture therein and the said lower portion being substantially 80 narrower than the upper portion. 75

10. As an article of manufacture, a plate holder having transverse flanges extending beyond the upper edge of the holder, and an elongated aperture between said flanges. 85

11. As an article of manufacture, a plate holder having depressions therein and having transverse flanges, said depressions being located parallel with said flanges and the body portion of said plate. 90

12. As an article of manufacture, a plate holder comprising a central portion having the edge portions thereof folded inwardly to define card holding and inking control means. 95

13. A plate holder comprising a body part having an aperture therein, a pair of flanges, one at either edge of said body part, said flanges being folded to lie parallel to said body part and the ends thereof being bent 100 at right angles to the folded portion of the flanges, the body part adjacent each flange being provided with a depression, a flap on said body part bent to lie thereover, a second flap having an aperture therein and 105 bent to lie upon the body portion, the edges of said flap being arranged adjacent said first mentioned aperture whereby the two apertures are arranged one above the other, the line of bending of said second flap being within the area defined by the ends of the two flanges whereby the latter will project above the body portion in the finished article. 110

14. A plate holder comprising a body 115 part having a large aperture therein, a pair of flanges, one at either edge of said body part, said flanges being folded to lie parallel to said body part and the ends thereof being bent at right angles to the folded portion of the flanges, the body part adjacent each flange being provided with a depression, a flap on said body part bent to lie 120 thereover, a second flap having an aperture therein and bent to lie upon the body portion, the edges of said flap being arranged adjacent said first mentioned aperture, whereby the two apertures are arranged one above the other, the line of bending of said second flap within the area defined by the 125 130

ends of the two flanges, whereby the latter will project above the body portion in the finished article, said second flap being provided with a set of retaining beads and a 5 slidable index tab mounted to engage and move along an edge of said second mentioned aperture.

15. A plate holder having a printing plate mounted thereon and having ribbed ends 10 with depressions extending longitudinal of the ribs, and an inking device having contact members adapted to occupy the depressions when the inking device is to be active and to be out of the depressions when said 15 device is to be inactive.

16. An individual address form holder having an embossed member mounted thereon and having its ends turned backwardly to make hollow ribs, there being depressions 20 extending longitudinal of the ribs, and an inking device having contact members adapted to occupy the depressions when the inking device is to be active and to be out of the depressions when said device is to 25 be inactive.

17. In a device of the character described, an individual address form holder having a printing member mounted thereon, and having means for controlling an inking 30 mechanism.

18. In a device of the character described, a holder having printing means mounted thereon, and having means for maintaining the ink roller of an inking mechanism out 35 of contact with the non-printing surfaces of said holder.

19. In a device of the character described, a holder having an embossed printing member mounted thereon, and having means for 40 maintaining the ink roller of an inking

mechanism out of contact with the unembossed surfaces of said member.

20. In a device of the character described, a holder having an embossed printing member mounted thereon, and means for controlling an ink roller including indented portions in said holder opposite the ends of said member, whereby cylindrical members mounted coaxially with said ink roller may loose contact with the surface of said 45 holder, and permit the ink roller to come into contact with the embossed sections of said member.

21. In a device of the character described, a plate holder, and means on the plate 55 holder adapted to coact with an inking device whereby, during the operation of printing, ink is supplied to a portion only of the plate holder.

22. A printing plate holder comprising 60 a body part having an identifying card secured thereon and also having a member provided with printing characters thereon, and means on said holder whereby an inking roller may be passed over the plate 65 holder to ink said printing characters without inking the identifying card.

23. In a device of the character described, a printing member comprising a plate holder having embossed printing characters associated therewith and having means thereon 70 for controlling an inking mechanism, whereby the inking mechanism may be moved toward the printing member only when the printing characters are beneath 75 said inking member.

In testimony whereof, I hereunto affix my signature.

CLIFTON CHISHOLM.

Certificate of Correction.

It is hereby certified that the assignee in Letters Patent No. 1,438,578, granted December 12, 1922, upon the application of Clifton Chisholm, of Cleveland, Ohio, for an improvement in "Address-Plate Holders," was erroneously described and specified as "American Multigraph Company," whereas said assignee should have been described and specified as *The American Multigraph Company*, as shown by the records of assignments in this office; and that the said Letters Patent should be read with this correction therein that the same may conform to the record of the case in the Patent Office.

Signed and sealed this 9th day of January, A. D., 1923.

[~~SEAL.~~]

KARL FENNING,

Acting Commissioner of Patents.
